W. A. KULL

MUFFLER

Original Filed Feb. 7, 1925

INVENTOR:
WALTER A. KULL,
BY
Blackmore, Spencer & Flint
HIS ATTORNEYS.

UNITED STATES PATENT OFFICE.

WALTER A. KULL, OF FLINT, MICHIGAN.

MUFFLER.

Application filed February 7, 1925, Serial No. 7,552. Renewed May 13, 1928.

This invention relates to mufflers and is herein shown as embodied in a muffler or silencer for reducing the noise of exhaust gases from an internal combustion engine.

An object of the invention is to provide a simple and efficient muffler which can be inexpensively made from sheet metal. Another object is to provide a muffler which will reduce the velocity of the gases and 10 more effectively silence the exhaust.

To these ends and also to improve generally upon devices of the character indicated my invention consists in the various matters hereinafter described and claimed.

15 In the drawings, Figure 1 is a central longitudinal section, partly broken away.

Figure 2 is an end view.

Figure 3 is a section on line 3—3 of Figure 1.

20 Figure 4 is a section on line 4—4 of Figure 1.

The numerals 10 and 12 indicate circular diaphragm members which are arranged in axial alignment and provided with concentric stepped portions 14, 16 and 18 projecting towards one another. The members are of like size and form so that they can be pressed out of sheet metal in the same dies. The member 10 is shown provided 30 with a central opening 20 and the member 12 with a series of openings 22 near its periphery. A tube 24, with perforations 26, has its ends sleeved over the steps 18 of smaller diameter outside of the central opening 20. The tube is preferably welded to one of said steps and left unsecured, as against longitudinal movement, with respect to the other.

A plate 28, having perforations 30, is 40 wrapped tightly around the intermediate steps 16 and provided with a longitudinal interlocking joint 32 which is folded down against the outer face at 34. This makes a cylinder which is preferably welded to the steps 16 and lies inside of the circle of openings 22 in the diaphragm member 12. An outer shell 36 is formed by bending a sheet metal plate into cylindrical form with a longitudinal interlocking joint 38 folded 45 against its outer face. The shell is preferably welded to the larger steps or flanges 14 of the diaphragms and extends axially beyond the diaphragms for a considerable distance.

50 Fixed within one end of the outer shell or plate 36, as by welding, is a flanged head

40 having an outlet opening communicating with a discharge pipe 42. A chamber 44 is thereby formed which receives the gases from the openings 22. Fixed within the 60 other end of the shell or plate 36 is a flanged head 46 having an inlet opening 48 which receives the burnt gases and delivers them into an expansion or pressure reducing chamber 50. This chamber is substantially 65 cylindrical and, having only the thin outer shell 36 between it and the atmosphere, the hot gases are initially cooled to a considerable extent and thus their velocity through the muffler is subsequently reduced. The 70 gases pass rearwardly through the opening 20 into tube 24, thence through perforations 26 and forwardly outside of tube 24 to the perforations 30 in the cylindrical plate 28 after which they again go rearwardly just 75 inside of the shell 36 to the openings 22.

Although the invention has been described by reference to a specific construction, it should be understood that, in its broader aspects, it is not necessarily limited to the 80 form selected for mere illustrative purposes.

I claim:

1. In a muffler, a pair of flanged diaphragm members arranged in axial alignment and having concentric stepped portions, one of said members being provided with an opening at its center and the other with openings near its periphery, a tube having its ends sleeved on the innermost stepped portions of the diaphragm, the interior of the tube communicating with the first named opening, said tube being provided with openings at the end removed from the first named opening, a cylinder having its ends sleeved on the next larger stepped portions, said cylinder being provided with openings therein at the end remote from the apertured end of the said tube, an outer cylindrical shell secured to the flanged portions of the said diaphragms and forming with said cylinder a chamber communicating with the interior of the cylinder at one end through the openings in said cylinder, and at the other end in communication with the peripheral openings in one of said diaphragms, said shell having its ends extended axially beyond the diaphragms, heads in the form of flanged discs secured in the ends of the shell and spaced a considerable distance from said diaphragms to form expansion chambers, one of said expansion chambers being provided

with an opening for the admission of exhaust gases and the other chamber being provided with an opening for the discharge of exhaust gases.

2. In a muffler, an outer tubular shaped member having openings in its ends, diaphragms internally located, one adjacent each end to form, with said ends, expansion chambers, a plurality of tubes between said diaphragms, the tubes having radial aper-

tures at alternate ends, one diaphragm having a central opening affording communication between one expansion chamber and the innermost tube, the other diaphragm having one or more peripheral apertures 15 affording communication between the external annular space within the outer wall and the second expansion chamber.

In testimony whereof I affix my signature.
WALTER A. KULL.
